INK MARKER OR THE LIKE

Noboru Wakai, 32-2 1-chome, Umeda-cho,
Adachi-ku, Tokyo, Japan

Filed Sept. 19, 1966, Ser. No. 3,912

Term of patent 14 years

(Cl. D74—17)

FIG.1

FIG.6

FIG. 1 is a top plan view of an ink marker or the like showing my new design;

FIG. 2 is an elevational view thereof;

FIG. 3 is a bottom plan view;

FIG. 4 is a fragmentary elevational view thereof as it appears with the cap removed;

FIG. 5 is a top plan view of FIG. 4; and

FIG. 6 is a bottom plan view of the cap portion.

I claim:

The ornamental design for an ink marker or the like, as shown.
